(57) **CLAIM**

I claim the ornamental design for a string necklace and bracelet protector, as shown and described.

DESCRIPTION

FIG. 1 is a front top isometric view of a string necklace and bracelet protector showing my new design;

FIG. 2 is a rear bottom isometric view thereof;

FIG. 3 is a top plan view thereof;

FIG. 4 is a bottom plan view thereof;

FIG. 5 is a front elevation view thereof;

FIG. 6 is a right side elevation view thereof; and,

FIG. 7 is a cross-sectional view, taken along line 7 in FIG. 3.

A design left side elevation view has been omitted, as it is a mirror image of the right side elevation view of FIG. 6. A design rear elevation view has been omitted, as it is a mirror image of the front elevation view of FIG. 5. The broken lines illustrate an environmental structure and forms no part of the claimed design.
